PATENTED SEPT. 1, 1908.

H. E. MADDEN.

VEGETABLE SLICING OR CUTTING MACHINE.

APPLICATION FILED OCT. 25, 1907.

UNITED STATES PATENT OFFICE.

HARLAND E. MADDEN, OF HEBRON, OHIO.

VEGETABLE SLICING OR CUTTING MACHINE.

No. 897,637.

Specification of Letters Patent.

Patented Sept. 1, 1908.

Application filed October 25, 1907. Serial No. 399,086.

To all whom it may concern:

Be it known that I, HARLAND E. MADDEN, citizen of the United States, residing at Hebron, in the county of Licking and State of Ohio, have invented certain new and useful Improvements in Vegetable Slicing or Cutting Machines, of which the following is a specification.

My invention relates to the improvement 10 of vegetable slicing or cutting machines and the objects of my invention are to provide a simple, reliable and effective machine of this class by means of which vegetables may be uniformly and rapidly sliced; to provide improved 15 means for regulating the thickness of the slice produced; to provide improved means for feeding the last slice of the potato or other vegetable into the discharge opening and to produce other improvements the de- 20 tails of which will be more fully pointed out hereinafter. These objects I accomplish in the manner illustrated in the accompanying drawing, in which:

Figure 1 is a central vertical section of my 25 improved machine, Fig. 2 is a detail view in perspective of the slicing table showing a portion of one of its side frame pieces broken away for the sake of clearness in illustration, Fig. 3 is a transverse section of the machine 30 on line $x-x$ of Fig. 1, Fig. 4 is a detail view in perspective of a cutting frame which I employ in the manner hereinafter described, Fig. 5 is a longitudinal section through a portion of one of the slicing frame side pieces 35 showing the manner of holding the cutter plate in place, and, Fig. 6 is an enlarged sectional view on line $y-y$ of Fig. 3.

Similar numerals refer to similar parts throughout the several views.

In carrying out my invention, I provide a 40 framework consisting of suitably supported and connected horizontal side frame bars 1 and on the inner side of each of these frame bars I provide a recess or kerf 2 in which 45 kerfs are slidably supported the laterally projecting flanges 3^a of the vertical and parallel sides 3^b of a slicing frame 3. The side pieces of the slicing frame 3 are connected at their ends by cross pieces 3^c of less 50 height than said sides. In the construction 55 of the said slicing frame side portions, the same are preferably produced of two sections which are united by bolts 4, the inner sections 3^d being as shown, in the nature of channel bars which have their outturned

side portions abutting against the inner faces of the outer sections.

5 represents a stationary cutter plate, the ends of which are removably supported in slotted openings formed longitudinally in the 60 inner sections of the side pieces 3^b at the centers of their lengths. This plate 5 is detachably held in its position across the center of the slicing frame, by means of a pin 6 which projects upwardly from the free end of a 65 spring strip 7 (see Fig. 5), the remaining end of which is secured to the underside of the top portion of one of the side pieces 3 of the slicing frame. This pin 6 passes through openings formed respectively in said cutter 70 plate and frame top. The plate 5 is provided on its underside with parallel cutting blades 8 which extend in the direction of the length of the machine and which are inclined from their outer ends upward to the under- 75 side of the cutter plate. The outer sections 3^b of the side frame pieces 3 are provided at intervals with oppositely located vertical slots 9 and through these slotted openings extend the laterally projecting pins 10 of 80 horizontal plates 11. There are two of these plates and they are arranged respectively in front and in rear of the plate 5. The plates 11 which form floor sections for the slicing frame are, as shown, supported below the 85 surface of the plate 5 and are adjustable vertically in the manner hereinafter described.

The outwardly projecting plate pins 10 are pivotally connected with the upper ends of links or short bars 12, the lower ends of 90 which are pivotally connected, as shown, with bars 13, these bars extending longitudinally, as shown, within the channels or housing formed by the uniting of the inner and outer sections of the side pieces of the slicing frame. The bars 13 extend through one end of the slicing frame and are connected with the end portions of a transverse adjusting bar 14, at the center of which is formed a threaded opening through which passes an 100 adjusting screw 15, the inner end of the latter being rotatably connected with the end 3 c of the slicing frame.

Near each end of the machine I bridge the slicing frame with a fixed transverse bar 16 105 through a threaded opening in which passes centrally a vertical adjusting screw 17, the latter being as shown more clearly in Fig. 6, rotatably connected at its lower end with a transverse bar 18 from the under side of 110

which depends a stop plate or apron 19, the height of the lower edge of the latter from the upper surface of the plate 11 being regulated by the rotation of said screw 17. Rising from the supporting framework of the machine at about the center of the length thereof are the vertical frame pieces 20 of a hopper, which vertical frame pieces are connected by horizontal frame pieces 20^a. This hopper frame supports a vertical casing 21 open at its upper and lower ends and within which is adapted to be moved vertically a plunger 22 which has a vertical handle or stem portion 22^a.

15 In the lower portion of the hopper casing, I support, through the medium of upwardly extending arms 23 which engage the upper end of the hopper casing, a cutting or shaping frame 24, the latter being in the nature of a square or oblong open frame and having one or more transverse knife bars 25 arranged between its sides. Upon this cutting frame 24 is adapted to be detachably supported an upper cutting frame 26 corresponding in construction with the frame 24 with the exception that the knife or knives 27 of said frame 26 extend at right angles with the knife bar 25.

30 At one end of the machine, I journal transversely in the supporting framework a shaft 28, the outer portion of which carries a driving wheel 29, which may have a crank projection for operation by hand or which may be otherwise rotated if desired. With the 35 rim portion of this wheel I pivotally connect a pitman 30 which, extending toward the opposite end of the machine is pivotally connected with a pin or rod 31 which in turn is connected with the end of the slicing frame.

40 In utilizing my invention the vegetables to be sliced are fed into the hopper and on to the upper cutting or shaping frame 26. By then pressing the plunger downward, it will be understood that the vegetable will be 45 forced through the openings formed by the crossed cutter blades 25 and 27, thus depositing the vegetable upon one of the plates 11 in sections, the slicing frame having previously been moved until one of said plates 50 11 is beneath the hopper. The rotation of the wheel 29 and consequent backward and forward sliding movement of the slicing frame, results in bringing the sections of the vegetable which rest upon the plates 11, in 55 contact with the transverse edges of the plate 5 and with the knife blades 8, the former slicing the vegetable horizontally and the latter cutting the slices thus formed vertically into desirable widths. It will be un-

derstood that the vegetables deposited on the plates 11 will be prevented from being forced off the end thereof by contact with the plates 19 and that these plates may be adjusted so that their lower edges are in such close proximity to the upper sides of the plates 11 as to engage the last comparatively thin slice of the vegetable. It is also obvious that the movement of the slicing frame described, will result in the slices which are formed being by contact with the plates 19, forced into and permitted to drop through the opening between the inner ends of the plates 11.

It will be understood that the thickness of the vegetable slice produced may be regulated by turning the screw 15, thereby moving the bars 13 longitudinally and, through the movement of the links 12, imparting an upward or downward adjustment to the plates 11. When it is desired to remove the 80 cutter plate 5, the pin 6 may be depressed until out of engagement with said cutter plate and the plate readily withdrawn.

In case the separation of the vegetable into comparatively small sections is not desired, and larger slices are to be produced, it is obvious that one or both of the cutter frames 24 and 26 may be lifted out of the hopper before the vegetables are introduced therein.

90 What I claim, is:

In a vegetable slicing machine, the combination with a supporting framework and a hopper mounted thereon, of a slicing frame slidably mounted in said framework, a fixed cutter plate extending between the sides of the slicing frame, floor plates on opposite sides of said cutting plate, slidably mounted longitudinal bars links pivoted to said bars and to said floor plates, a transverse bar connecting the ends of said longitudinally disposed bars, an adjusting screw engaging a threaded opening in said transverse bar and engaging one end of the slicing frame, and means for imparting a reciprocatory motion to said slicing frame, said floor plates lying between the sides of the slicing frame and said longitudinal bars lying upon the outer sides of the slicing frame, there being slots formed in the sides of the slicing frame through which the pivots that connect the links to the floor plates, pass.

100 In testimony whereof I affix my signature in presence of two witnesses.

HARLAND E. MADDEN.
